UNITED STATES PATENT OFFICE.

WALLACE BRUCE JOSEPH ROBERTSON, OF EDGBASTON, ENGLAND.

PRESSING OF PEAT AND THE LIKE.

1,415,398.

Specification of Letters Patent.

Patented May 9, 1922.

Application filed May 14, 1921. Serial No. 469,751.

To all whom it may concern:

Be it known that I, WALLACE BRUCE JOSEPH ROBERTSON, a subject of the King of Great Britain and Ireland, residing at 5 Monument Road, Edgbaston, in the city of Birmingham, England, have invented certain new and useful Improvements Relating to the Pressing of Peat and the like, of which the following is a specification.

10 This invention has for its object to provide a machine for compressing peat and the like into blocks, and also to arrange in conjunction with such a machine means for automatically feeding the same with raw material, which means may be adapted to cut or otherwise excavate the material from the

20 In the three accompanying sheets of explanatory drawings, Figure 1 is a diagrammatic side elevation showing the general arrangement of a peat machine constructed in accordance with this invention.

25 Figures 2 and 3 are respectively longitudinal section and part sectional plan showing diagrammatically the charging and compressing mechanism.

30 A rotatable table *a* is provided with a number of compression boxes *b* each containing a plunger *c*. Each plunger is fitted with a stem *d* arranged to co-operate with a fixed cam *e*. A spring *f* on the stem serves to produce the opposite movement of the plunger to that obtained from the cam. The table is carried by a ring *g* and rollers *h*, *i* serve 35 to take the vertical and lateral thrusts between the table and ring. Rotation of the table is effected by a toothed bevel ring *j* which is engaged by a half pinion *k* (that is a pinion whose teeth extend around only one 40 half of its periphery). During one half revolution of the pinion motion is imparted to the table, and during the other half revolution the table is stationary. The amount of movement given to the table in each active 45 half revolution of the pinion is equal to the angular distance between the compression boxes.

50 In conjunction with the table is arranged a charging box *l* fitted with a plunger *m* actuated through a rod *n*, connecting rod *o*, crank disc *p*, and bevel pinions *q* from a shaft *r* which also carries the half pinion *k*. The arrangement of the mechanism is such 55 that the plunger *m* is moved forward for charging a compression box while the table is stationary and returned while another

compression box is being brought into position.

Above the charging box is arranged a hopper *s* fitted with teasing rollers *t* which break up the peat supplied to the hopper and deliver it into the charging box.

Following the cycle of operations, a quantity of peat is fed from the hopper into the charging box. This is transferred by the plunger *m* to the compression box which is opposite the outer end of the charging box. During the return of the plunger for the reception of another charge from the hopper, the table is moved through a sufficient angular distance to bring another compression box into position. During this movement a sliding door *u* (with which the outer end of each compression box is fitted) is moved from the open to the closed position across the outer end of the compression box. This movement may be effected in any convenient manner. A simple device as shown in the drawing consists of a pinion *v* carried on the box and engaging a rack *w* along the upper edge of the door. As soon as the table begins to move from the charging position this pinion engages a stationary rack *x*, and by its movement relatively to that rack causes the door to be closed.

85 During the subsequent movements of the table the contents of the charged box is gradually compressed by the advance of the plunger *c* in the box under the action of the fixed cam *e*. When the box is approaching the discharge position the shape of the cam *e* is such that the pressure of the plunger *c* is released and the pinion *v* engages another fixed rack *y* which causes the door to be opened. In the next movement of the table 90 the compressed block of peat is discharged. The discharge position is shown by *z* in Figure 3, and in the next position the now empty box receives another charge. Each compression box passes in turn through the 95 same cycle.

100 Preferably the apparatus above described is mounted on a portable frame 2 which is provided on each side with an endless track chain 3 or the like for supporting and moving the frame. Also the frame may be fitted with an internal combustion engine 4 driving a dynamo 5. The latter supplies current to an electric motor 6 which operates reduction gear contained in a box 7 and also 110 a worm gear 8 for actuating the track chain. Motion is transmitted by a chain 9 to the

shaft r . The rollers t may also derive their motion from the mechanism in the box 7, or they may be driven by a separate electric motor receiving current from the dynamo 5.

5 For charging the feed hopper a suitable frame structure 10 is arranged adjacent to the hopper and on this structure is carried a laterally projecting arm 11 which can be raised and lowered on the said structure as required. The arm carries a truck 12 from which is suspended a grab 13 or other cutting, excavating or conveying device which is actuated by gearing on the truck, the gearing being driven by an electric motor receiving current from the dynamo. The grab or the like is caused to travel along the arm for the purpose of transferring peat raised from the earth to the charging hopper. If desired the arm 11 or the structure 10 which carries it may be rotatable relatively to the frame. When fixed as shown, change of the position at which the grab or the like receives the peat is effected by maneuvering the whole machine.

25 The invention is not limited to any particular mechanical or constructional details as these may be varied to meet different requirements.

Having thus described my invention what 30 I claim as new and desire to secure by Letters Patent is:—

1. In machines for compressing peat and the like, the combination of an intermittently rotatable compression box, a plunger in the box, a fixed cam acting in one direction on the plunger for compressing and ejecting the contents of the box, a spring acting on the plunger in the opposite direction for returning the plunger, a door on the outer end of the box, and means for charging the box with the material to be compressed, substantially as described.

2. In machines for compressing peat and the like, the combination of an intermit-

tently rotatable compression box, a plunger 45 in the box, a fixed cam acting on the plunger for compressing and ejecting the contents of the box, a slideable door at the outer end of the box, a rack on the door, a toothed pinion on the box, a pair of fixed racks 50 which by movements of the pinion relatively to the same impart opening and closing movements to the door, and means for charging the box with the material to be compressed, substantially as described. 55

3. In machines for compressing peat and the like, the combination of an intermittently rotatable table, a plurality of radially disposed compression boxes on said table, a plunger in each box for compressing and 60 ejecting the contents of the box, a centrally placed stationary cam acting on all the plungers of the compression boxes in the outward direction, a spring in conjunction with each plunger for moving the same in the inward direction, a slideable door on the outer end of each box, a rack on each door, a pinion on each box engaging said rack, a pair of fixed racks which are engaged in turn by each pinion for opening and closing the 70 doors, an annular support for the table, a toothed wheel in conjunction with the table, a half toothed wheel engaging the toothed wheel on the table and producing intermittent movements of the table, a charging box, 75 a hopper communicating with the charging box, a plunger in said box for transferring material from the same to each compression box in turn, a crank disc and a connecting rod for actuating the charging box plunger, a pair of toothed wheels for operating the crank disc, and a driving shaft carrying one of said wheels and the aforesaid half toothed wheel for operating the table, substantially as described. 85

In testimony whereof I have signed my name to this specification.

WALLACE BRUCE JOSEPH ROBERTSON.
